UNITED STATES PATENT OFFICE.

WILLIAM COOK, OF NEW YORK, N. Y., ASSIGNOR TO GEORGE S. TERRY, OF NEW YORK, N. Y.

APPARATUS FOR BUILDING WALLS.

1,033,385.

Specification of Letters Patent. Patented July 23, 1912.

Application filed May 12, 1909. Serial No. 495,396.

To all whom it may concern:

Be it known that I, WILLIAM Cook, a citizen of the United States, and resident of the borough of Manhattan, in the city and State of New York, have invented a new and useful Apparatus for Building Walls, of which the following is a specification.

This invention relates to apparatus for building walls, and in particular to that class of apparatus used in constructing walls of reinforced concrete.

One of its objects is to provide means for utilizing the building uprights as supports for the mold plates of the apparatus.

Another object is to provide means for vertically adjusting the mold plates on the building uprights.

A further object is to provide means supported from the building uprights for truing the mold plates, together with means carried by the mold plates for retaining them in the position in which they are forced by the truing means.

A further object is to provide means removably carried by the mold plates for partially filling the space between the said plates so as to produce a honeycombed wall.

A further object is to provide projections on the inner face of the mold plates for creasing the wall to produce an effect in imitation of a wall composed of stone blocks.

A still further object is to provide certain improvements in the form, construction and arrangement of the various parts whereby the above objects may be effectively carried out. A practical embodiment of my invention is represented in the accompanying drawings, in which—

Figure 1 represents a side elevation of a portion of a wall with my apparatus thereon, parts being broken away to show the interior, Fig. 2 represents an end view of the parts shown in Fig. 1, a portion being broken away, Fig. 3 represents a top plan view of the parts shown in Fig. 1, Figs. 4, 5 and 6 represent detail end, top plan and side views, respectively, of the means for supporting the mold plates from the building uprights, together with means for adjusting the mold plates. Figs. 7, 8 and 9 represent detail end, top plan and side views, re-

spectively, of one of the removable cores in position on the mold plate, Figs. 10 and 11 are detail end and side views, respectively, of one of the clamps carried by the mold plates for holding them in the position in which they are forced by the adjusting means, Figs. 12 and 13 are detail side and top plan views, respectively, of a right angle section of the mold plates, and Fig. 14 is a detail view of the inner face of the outer mold plate.

The building uprights are indicated by 1 and have enlarged bed plates 2 at their lower ends. The uprights are shown, in the present instance, as tubular; gas pipe being a very convenient material for this use. Yokes 3 are fitted to slide longitudinally on the uprights, and are provided with set screws 4 for securing them in any desired adjustment thereon. Depending from these yokes at opposite sides of the uprights, are hangers 5, which are arranged to be adjusted on the yokes laterally with respect to the uprights, and may be secured in any desired position on the yokes by the set screws 6. These hangers are adapted to receive the outer ends of screw bolts 7, set in the mold plates 8, for securing the plates to the hangers; and are also provided with adjusting screws 9 for truing the mold plates and keeping them perfectly plumb.

The mold plates 8 are preferably composed of sheet iron and are provided with angle irons bolted along their upper and lower edges. These plates may be made of any desired length by bolting the sections together, as indicated at 10. The outer mold plate is provided, along its inner face, with upper and lower projections 11, 12, for producing creases in the wall molded against them. The upper projection has the cross sectional shape of a right-angled triangle, while the lower projection has the cross sectional shape of an equilateral triangle; the upper projection being intended to form the lower bevel of a crease at the top of each course of wall, and, the under face of the lower projection is intended to rest on the bevel thus formed, while its upper face forms the other bevel of the crease as the next course of wall is molded. Tapered cores 13 are secured to cross bars

14, which bars are adapted to be removably attached to the angle irons of the mold plates 8, at any desired positions along said plates, by means of clips 15, and thumb nuts 16. The bars 14 serve the double purpose of supporting the cores 13 and also holding the mold plates against spreading when it is desired to tamp the wall as it is molded. These cores are intended to project downwardly and partially fill the space between the mold plates, so as to leave holes in each course as it is molded, and thus produce a honeycombed wall.

Tapered plugs 17 are provided for closing the tops of the holes in each course, so that the material used in constructing the course next above will not fill the holes in the lower course. Clamps for holding the mold plates in their trued positions are arranged to be located at intervals along the mold plates, and comprise side bars 18, and upper and lower cross bars 19 and 20. The side bars are provided at their lower ends with blocks 21 so that the side bars may press against the mold plate proper as well as against the edge of the lower angle iron on the mold plate. The lower cross bar 20 is provided with a pin and hole adjustment with the side bars 18, and the upper cross bar 19 is provided with a pin and hole adjustment with one of the side bars 18 and a screw threaded adjustment with the other of the side bars 18. By leaving the lower cross bar 20 in a fixed adjustment, the lower ends of the side bars may be swung inwardly by adjusting the upper cross bar 19, thus producing the desired pressure on the mold plates, and assisting the adjusting screws 9 in keeping the said plates plumb. If desired, wires 22 may be strung from upright to upright between each course of wall, for lending strength to the completed structure.

In operation, the uprights 1 are placed in the desired location, and anchored by any suitable means, such, for instance, as a foundation layer of concrete. The yokes 4 are then placed on the uprights and secured in proper position for molding the first course. The mold plates are then secured to the hangers 5 and trued up by the screws 9, and clamped in place by the clamps comprising the members 18, 19, 20, 21. The wire 22 may be strung in place, and the cores 13 secured at proper points on the mold plates. The concrete is then poured in between the mold plates up to the top thereof. After the concrete has hardened, the cores 13 are removed and the holes left by them closed by means of plugs 17. The whole molding apparatus may then be raised with the yoke 4 along the uprights and secured in place for molding the next course of wall, when the operation may be repeated. The uprights 1 are intended to

remain permanently in the wall to give it strength, and they thus perform the function of regular building uprights, as well as supporting means for the mold apparatus. By using the cores 17 I may produce a honeycombed wall thus saving a considerable amount of building material. These cores may be spaced at any desired intervals one from the other, in order to produce a greater or lesser number of holes in the wall. The adjustment of the hangers 6 on the yokes 4 is provided for molding walls of different thicknesses.

While I have shown the projections on the inner face of the outer mold plate as being elongated and having the cross sectional form of triangles, it is to be understood that I may use any kind of projections of any length and of any cross section in place of the one shown; or I may omit the projections entirely and use the mold plates plain; or with merely roughened faces to make a wall having an exterior surface in imitation of the surface of stone.

It is obvious that certain changes may be resorted to in the form, construction and arrangement of the various parts of my device without departing from the spirit and scope of my invention; hence I do not wish to limit myself strictly to the form herein shown and described.

What I claim is:—

1. In apparatus of the character described having building uprights, mold plates provided with lateral extensions at their tops, means for supporting the plates from the building uprights, means for truing the plates also supported from the building uprights independently of the plates, removable cores carried by the plates for partially filling the space between them, said cores being provided with clips fitted to engage the said lateral extensions of the plates for securing the cores in position thereon.

2. In apparatus of the character described having building uprights, mold plates provided with lateral outward extensions at their lower edges, means for supporting the plates from the building uprights, means for truing the plates also supported from the building uprights, and clamps for holding the plates in their trued position, the said clamps being provided with blocks fitted to engage the said lateral extensions of the plates, whereby the clamps may be carried by the plates.

3. In apparatus of the character described having building uprights, mold plates provided with lateral outward extensions at their lower edges, means exterior to the plates for supporting them from the building uprights, means for truing the plates also supported from the building uprights and independently of the plates, and

clamps for holding the plates in their trued positions, the said clamps being provided with blocks fitted to engage the lateral extensions of the plates, whereby the clamps are carried by the plates.

In testimony that I claim the foregoing as my invention, I have signed my name in

presence of two witnesses, this seventh day of May 1909.

WILLIAM COOK.
